LAMP MOUNTING UNIT

Milton R. Revzin, Youngstown, Ohio

Application November 27, 1956, Serial No. 43,962

Term of patent 14 years

(Cl. D48—4)

Fig. 1

Figure 1 is a side elevation of a lamp mounting unit showing my new design with the broken lines showing a shade being for illustrative purposes only; and

The back of the bracket is plain and the opposite side of said member is the same in appearance as the side shown except for the knob element.

I claim:

The ornamental design for a lamp mounting unit, as shown and described.
